UNITED STATES PATENT OFFICE

GARLAND LUFKIN, OF TOLEDO, OHIO, ASSIGNOR TO OWENS-ILLINOIS GLASS COMPANY,
A CORPORATION OF OHIO

LEER FOR ANNEALING GLASSWARE

Application filed August 26, 1930. Serial No. 477,869.

The present invention relates to improvements in leers for annealing glassware and particularly to that type in which the articles of glassware to be annealed are carried through an elongated tunnel or chamber wherein the temperature decreases gradually in a predetermined manner from the receiving end to the delivery end.

In operating leers of the above type, articles of glassware are placed in the receiving end of the tunnel or chamber where the temperature may be approximately 1000° F., and subjected to a reheating process by which strains and stresses are removed from the glass structure. From the receiving end to the delivery end the temperature gradually drops so that the articles of glassware moving therethrough are uniformly cooled internally and externally with the result that upon reaching atmospheric temperature the articles are substantially free from strains and stresses. The cooling of the articles of glassware down to a predetermined temperature (approximately 500° to 600° F.) must be comparatively slow. Beyond this point the articles may be cooled as rapidly as possible without any detrimental effects on the quality of the glass.

An object of the present invention is the provision of novel means for cooling portions of the leer tunnel for the purpose of accelerating cooling of the articles of glassware therein so that they may be handled without difficulty by the operators.

Another object is the provision of cooling means embodying apparatus for causing flow of cooling medium in regulable quantities over variable exterior areas of a wall or walls of a leer tunnel. To this end the cooling section of the tunnel includes an uninsulated metal roof upon which is arranged a longitudinal series of open ended flues extending transversely of said roof. With these flues is associated means for drawing regulable quantities of cool outside air or the like into the ends thereof for the purpose of cooling the roof and by conduction removing heat from within the leer tunnel or chamber. Thus the temperature within the tunnel may be controlled.

Other objects will be in part apparent and in part pointed out hereinafter.

In the drawing:

Fig. 1 is a sectional elevational view illus-

trating the embodiment of my invention in a leer of conventional form.

Fig. 2 is a detail sectional elevational view illustrating more particularly the structure employed in my leer cooling apparatus. 60

Fig. 3 is a transverse sectional view taken substantially along the line III—III of Fig. 2.

The leer in conjunction with which my invention is illustrated, is of conventional form and comprises a tunnel 5 or annealing chamber mounted on a wheeled frame 6. The leer tunnel comprises side walls 7 and a roof 8 formed of sheet metal. Certain areas, particularly in the vicinity of the receiving end, 65 are suitably insulated by slabs 9 of insulating material. The remaining areas, including sides and top, may be and preferably are uninsulated to increase dissipation of heat. A leer conveyor 10 extends through the tunnel 70 5 for the purpose of carrying articles of glassware through the various heating and cooling zones, the article supporting reach being arranged in the lower area of the tunnel. The leer may be heated by electrical 75 heating elements 11 or other devices arranged in proximity to the receiving end of the leer. 80

Articles of glassware placed upon the leer conveyor 10 are slowly transported through the leer tunnel from the receiving end "E" 85 to the delivery end "D". During passage through the leer the articles of glassware are heated to remove strains and stresses in the glass structure and then are allowed to cool gradually until they reach a predetermined 90 temperature, beyond which the cooling may be effected as rapidly as possible. For the purpose of accelerating cooling of the ware and creating in the cooling zone "C" the desired temperature gradient, there is provided 95 in the present invention, means for causing impingement of regulable quantities of cooling air or the like upon variable areas of the leer roof 8. For this purpose the metal roof 8 in the cooling zone is uninsulated and provided with flues or conduits 12, one wall of which is formed by the metal roof 8. These flues or conduits are arranged side by side and extend transversely of the leer roof 8, terminating substantially at the side edges of 100 the roof plate. A header or suction pipe 13 is arranged above the series of flues 12 and extends lengthwise along the center line of the leer. Pipe connections 14 individual to the flues 12 are provided between the latter 105

110

and said header pipe, each of said flues being equipped with a manually operable damper 15. Preferably, the pipe connections 14 provide communication between header pipe 13 and the central portions of the flues. A suction fan 16 is suitably connected to one end of the header pipe 13 for the purpose of exhausting air from the header pipe 13 and connections 14 so that outside air will be drawn 10 into the open ends of the flues 12. Thus the metal roof plate 8 comprising the roof of the cooling zone "C", is cooled and conducts heat from the leer tunnel to the flues from which suction removes it to the atmosphere by way 15 of the header pipe 13.

In operating the cooling means, the dampers 15 are adjusted to regulate and control the effectiveness of the suction in the series 20 of pipe connections 14 so that air in variable quantities enters the open ends of the flues 12. By providing dampers individual to the pipe connections it is evident that almost any desired temperature gradient in the cooling zone "C" may be obtained and the rate of 25 cooling accelerated or retarded as conditions demand. With the dampers properly adjusted and the suction fan 16 operating, cool outside air or other cooling medium is drawn into the open ends of the flues and thence 30 through the pipe connections 14 to the header or suction pipe 13 and by way of the fan to the atmosphere. During movement of the outside air through the flues it impinges upon the metal roof plate 8 and tends to cool the 35 latter. Due to the temperature differential created the roof plate conducts heat from within the leer tunnel to the interior of the flues, such conducted heat being then drawn off by the apparatus illustrated.

40 Modifications may be resorted to within the spirit and scope of the appended claims.

What I claim is:

1. A glassware annealing leer comprising an elongated tunnel having an uninsulated 45 metallic wall, means including portions of said wall providing a series of open ended flues, said flues extending transversely of the tunnel, means for drawing a cooling medium into said flues through the open ends thereof 50 to control the temperature in the tunnel, and adjustable means for varying the effectiveness of the flues.

2. A glassware annealing leer comprising an elongated tunnel having an uninsulated 55 metallic wall, means including portions of said wall providing a series of open ended flues, said flues extending transversely of the tunnel, a header pipe, connections individual to the flues providing communication between the central portions of the latter and said header pipe, and means for applying suction to the header pipe and connections and thence to said flues.

3. A glassware annealing leer comprising an elongated tunnel having an uninsulated metallic wall, means including portions of said wall providing a series of open ended flues, said flues extending transversely of the 70 tunnel, a header pipe, connections individual to the flues providing communication between the central portions of the latter and said header pipe, means for applying suction to the header pipe and connections and thence 75 to said flues, and dampers individual to the connections.

4. A glassware annealing leer comprising a tunnel including side and top walls, and means including flues extending transversely 80 of the tunnel for directing cooling medium over the outer surface of one of the walls, said flues having open ends providing direct communication between the interior of the flues and the atmosphere.

5. A glassware annealing leer comprising a tunnel having a metallic roof, a portion of which is uninsulated, a longitudinal series of flues arranged on the outer surface of the roof and extending transversely of the leer, said 90 flues having inlet openings at their ends and an outlet opening centrally located between said ends, a suction pipe over the series of flues, connections individual to the flues providing communication between the outlet 95 openings and suction pipe, and means for applying suction to the pipe, connections and flues.

6. A glassware annealing leer comprising a tunnel having a metallic roof, a portion of which is uninsulated, a longitudinal series of flues arranged on the outer surface of the roof and extending transversely of the leer, said flues having inlet openings at their ends and an outlet opening centrally located between 100 said ends, a suction pipe over the series of flues, connections individual to the flues providing communication between the outlet openings and suction pipe, means for applying suction to the pipe, connections and flues, 105 and adjustable dampers individual to the flues.

7. A glassware annealing leer comprising a tunnel having an uninsulated metallic wall, and means employing suction for applying a 110 cooling medium to the outer surface of said wall, said means including a series of open ended flues extending transversely of the tunnel and in part formed by said metallic wall.

8. A glassware annealing leer comprising a tunnel having an uninsulated metallic wall, means employing suction for applying a cooling medium to the outer surface of said wall, said means including a series of open ended flues extending transversely of the tunnel and 125 in part formed by said metallic wall, and adjustable dampers individual to the flues.

GARLAND LUFKIN.
